UNITED STATES PATENT OFFICE.

JOHN P. ODGERS, OF PHILADELPHIA, PENNSYLVANIA, ASSIGNOR TO THE
A. M. COLLINS MANUFACTURING COMPANY, OF SAME PLACE.

DESIGN FOR A PHOTOGRAPHIC CARD-MOUNT.

SPECIFICATION forming part of Design No. 30,514, dated April 4, 1899.

Application filed February 20, 1899. Serial No. 706,269. Term of patent 7 years.

To all whom it may concern:

Be it known that I, JOHN P. ODGERS, a citizen of the United States, residing at Philadelphia, Pennsylvania, have invented and produced a new and original Design for a Photographic Card-Mount, of which the following is a specification.

My design is fully shown in the accompanying drawing, which represents the design as applied to a rectangular card.

The essential feature of the design is a border having a roughened or granular groundwork, upon which are figures in relief consisting of leaves and scrolls, a subordinate feature of the design being a central bevel-edged panel.

In the drawing, 1 represents the roughened

or granular groundwork of the border, 2 the leaves, and 3 the scrolls in relief thereon, and 4 represents the central panel, with beveled ²⁰ edge 5.

Having thus described my invention, I claim and desire to secure by Letters Patent—

The design for a photographic card-mount, ²⁵ substantially as herein set forth.

In testimony whereof I have signed my name to this specification in the presence of two subscribing witnesses.

JOHN P. ODGERS.
